Specification for Design.

Patented Oct. 24, 1916.

Application filed August 21, 1916. Serial No. 116,206. Term of patent 3½ years.

To all whom it may concern:

Be it known that I, CHARLES A. WESTOVER, a citizen of the United States, residing at Youngstown, in the county of Mahoning and State of Ohio, have invented a new, original, and ornamental Design for Tires, of which the following is a specification, reference being had to the accompanying drawing, forming part thereof, and in which drawing—

Figure 1 is a plan view of a portion of the tire showing my new design. Fig. 2 is a fragmentary sectional view on the line 2—2 of Fig. 1.

I claim:

The ornamental design for a tire, as shown.

CHARLES A. WESTOVER.
